UNITED STATES PATENT OFFICE.

AUSTIN F. JACKSON, OF TAUNTON, MASSACHUSETTS, ASSIGNOR TO THE
REED & BARTON CORPORATION, OF SAME PLACE.

DESIGN FOR BACK OF BRUSHES, &c.

SPECIFICATION forming part of Design No. 20,472, dated January 6, 1891.

Application filed November 17, 1890. Serial No. 371,744. Term of patent 7 years.

To all whom it may concern:

Be it known that I, AUSTIN F. JACKSON, a citizen of the United States, residing at Taunton, in the county of Bristol and State of Massachusetts, have invented and produced 5 a new and original Design for Backs of Brushes, Mirrors, &c., of which the following is a specification, reference being had to the accompanying illustration, forming part 10 thereof.

The figure is a photographic illustration of the back of a brush or hand-mirror embodying my design.

My design for backs of hair-brushes, hand-mirrors, &c., consists of a paddle-shaped outline with waved edges, having a marginal band *a*, terminating in scrolls *b b* at the point of union with the handle. Between these scrolls is a plain shield or oval panel *c*, and 15 surmounting the latter is a bunch of flowers *d*. Between the flowers *d* and the upper end of

the back is the representation of a grotesque human face *e*, merged centrally within and surrounded by arabesque ornamentation. The handle is of a spirally-twisted or roped 25 pattern *f*, and the end of the handle is covered with a cap of leaves *g*.

The leading feature of my design is the grotesque face *e*, the bunch of flowers *d*, and the marginal border terminating in scrolls *b b*, the 30 handle portion being subordinate and non-essential.

What I claim is—

1. The design for the backs of brushes, hand-mirrors, &c., as herein shown and described. 35
2. The design for the backs of brushes, hand-mirrors, &c., consisting of the ornamentations *a b c d e*, as herein shown and described.

AUSTIN F. JACKSON.
